UNITED STATES PATENT OFFICE.

ROBERT F. METCALFE, OF ERIE, PENNSYLVANIA.

CONTROLLING DEVICE FOR BOILER FURNACES.

1,422,369.

Specification of Letters Patent. Patented July 11, 1922.

Application filed July 25, 1919. Serial No. 313,419.

To all whom it may concern:

Be it known that I, ROBERT F. METCALFE, a citizen of the United States, residing at Erie, in the county of Erie and State of Pennsylvania, have invented new and useful Improvements in Controlling Devices for Boiler Furnaces, of which the following is a specification.

This invention relates to controlling devices for boiler furnaces and consists in certain improvements in the construction thereof as will be hereinafter fully described and pointed out in the claims.

The invention is particularly designed for use in boiler furnaces injecting liquid fuel with compressed air.

The invention is illustrated in the accompanying drawings as follows:

Fig. 1 shows a diagram of the apparatus in place.

Fig. 2 a section of the air controlling device, the cover of the valve chest being removed to better show construction.

Fig. 3 a section on the line 3—3 in Fig. 2.

Fig. 4 a section on the line 4—4 in Fig. 2.

Fig. 5 a view of a second burner.

1 marks the boiler, 2 the boiler furnace, 3 one burner, 4 the fuel supply tank, 5 the fuel and air jet, 5^A a pipe leading from the fuel supply tank to the jet, 7 the air pipe leading to the jet, 6 a pipe connecting the pipe 7 with the air control device 13, 8 an air tank, 9 a compressor supplying air to the air tank by means of a pipe 10, 11 a pipe connecting the air tank with an air controlling device 13, and 12 a throttle valve in the air pipe 11. Preferably there is a plurality of burners. These are in alignment and an air supply pipe 6^A leads to a second burner 3^A and a fuel supply pipe 5^B leads to the second burner. The two burners are exactly alike each having a jet 5 to which the pipe 7 leads, the burners being of any desired construction.

45 A pipe 14 leads from the steam space of the boiler to the air controlling device. The air controlling device is mounted on a frame 15. This terminates at its lower end in a flange 16 on which is mounted a diaphragm

50 17. A plate 18 is arranged over the diaphragm forming a pressure chamber 19. The pipe 14 delivers steam under boiler pressure to the chamber 19 in position to operate on the diaphragm. A stem 20 extends upwardly from the diaphragm and is moved as the diaphragm moves. A spring 21 re-

sists the movement of the diaphragm, or in other words, opposes the boiler pressure. This spring is seated on a collar 22 loosely mounted on the stem 20 and an adjusting screw 23 is provided by means of which the tension of the spring 21 may be varied. The stem 20 extends through a gland 24 in the frame 15 and into a valve chamber 25. The stem 20 operates against a lever 26, the lever being mounted on the pin 27. The end 28 of the lever operates on a valve lever 29, the valve lever being mounted on a pin 30. It will be readily observed that the lever 26 is so arranged with relation to its point 65 of operation on the lever 29 and the point of operation of the stem 20 that it gives to the end of the lever 29 a greater movement than that of the stem 20. This is desirable in that it permits of the use of the dia- 70 phragm without subjecting the diaphragm to an excess movement.

The lever 29 is held in its initial position by a spring 31, the spring operating on an arm 32 extending from the lever 29, the 80 spring being secured to a pin 33 extending from the bottom of the valve chest.

A valve 34 is mounted on the end of the lever 29 and operates over a valve face 35 in the bottom of the valve chest. Chambers 36 85 and 37 are arranged immediately back of the valve chest and the openings 38 and 39 form valve passages between the valve chest and these chambers. The pipe 6 extends from the chamber 36 and the pipe 6^A from 90 the chamber 37.

When the pressure in the boiler exceeds the desired normal the valve 34 is moved covering more or less of the openings 38 cutting off a portion of the air to the first 95 burner 3. If the pressure continues to rise it closes off all the openings 38 and more or less of the openings 39, thus reducing the fire in the second burner. On the reduction of pressure in the boiler the return movement of the valve due to the yielding of the diaphragm under the influence of the spring 21 opens the openings 39 and then the openings 38 so as to increase the fire.

It is desirable to maintain combustion in 105 the burners with as small a flame as possible so that there may be no trouble with pre-ignition when the burners are again put into normal operation. This is accomplished with relation to the first burner 3 by extending a bypass from the bottom of the valve chest to the chamber 36. This bypass may 110

be adjusted by the valve 41 so as to deliver just sufficient air to maintain combustion in the first burner. A similar bypass 42 extends from the valve chest to the chamber 5 37 and is controlled by a valve 43 and operates in the same way as the bypass 40.

The valve 34 is preferably yieldingly and rotatively mounted in the end of the valve lever 29. The valve has a stem, or projection 44 which is slidingly and rotatively mounted in an opening 45 in the end of the valve lever. A spring 46 yieldingly presses the valve against the valve face.

What I claim as new is:—

15 1. In a controlling device for boiler furnaces, the combination of a boiler; a burner leading to said boiler; means for supplying air to said burner; and a controlling device for the air comprising a valve chest having a 20 valve face therein with a series of controlling passages through the face; a valve mounted to slidingly operate over said face and to successively operate on said openings; a pressure device controlled by boiler pressure; and means actuated by the pressure device to actuate said valve.

2. In a controlling device for boiler furnaces, the combination of a boiler; a burner leading to said boiler; means for supplying air to said burner; and a controlling device for the air comprising a valve chest having a valve face therein; a valve swingingly mounted in the valve chest to operate over said valve face; a pressure device controlled by boiler pressure; and means actuated by the pressure device and acting on said mounting for operating said valve.

3. In a controlling device for boiler furnaces, the combination of a boiler; a plurality of burners leading to said boiler; means for supplying air to said burners; and a controlling device for the air comprising a pressure device controlled by the boiler pressure; and mechanism controlled by the pressure device for successively varying the supply to said burners.

4. In a controlling device for boiler fur-

naces, the combination of a boiler; a plurality of burners leading to said boiler; means for supplying air to said burners; and a controlling device for the air comprising a pressure device controlled by the boiler pressure; mechanism controlled by the pressure device for successively varying the supply to said burners; and devices for supplying air to said burners irrespective of the position of said mechanism sufficient to maintain combustion.

5. In a controlling device for boiler furnaces, the combination of a boiler; a burner heating said boiler; means for supplying air to said burner; and a controlling device for the air comprising a diaphragm subjected to the boiler pressure; a valve controlling the air; a lever actuating the valve; a second lever actuating the first lever; and means for communicating the movement of the diaphragm to the second lever.

6. In a controlling device for boiler furnaces, the combination of a boiler; a burner heating said boiler; means for supplying air to said burner; a controlling device for the air comprising a valve chest having a valve face thereon; a valve lever having a pivotal mounting at right angles to the plane of the valve face; a valve yieldingly mounted on the lever and operating on said face as the lever sweeps over the face; and a pressure device controlled by boiler pressure actuating said lever.

7. In a controlling device for boiler furnaces, the combination of a boiler; a burner heating said boiler; means for supplying air to said burner; a controlling device for the air comprising a valve chest having a valve face thereon; a valve lever; a valve yieldingly and rotatively mounted on the lever operating on said face; and a pressure device controlled by boiler pressure actuating said lever.

In testimony whereof I have hereunto set my hand.

ROBERT F. METCALFE.
